[57] **CLAIM**

The ornamental design for a golf club head, as shown and described.

DESCRIPTION

FIG. 1 is a perspective view showing the top, front and toe of a golf club head showing our new design; FIG. 2 is a top plan view of the FIG. 1 head; FIG. 3 is a front face elevation view of the FIG. 1 head; FIG. 4 is a bottom plan view of the FIG. 1 head; FIG. 5 is a toe and elevation view of the FIG. 1 head; FIG. 6 is a heel end elevation view of the FIG. 1 head; FIG. 7 is a rear elevation view of the FIG. 1 head; FIG. 8 is a top plan view of a second embodiment of the golf club head having a varied face inclination; FIG. 9 is a front face elevational view of the FIG. 8 head; FIG. 10 is a bottom plan view of the FIG. 8 heads; FIG. 11 is a toe end elevational view of the FIG. 8 head; FIG. 12 is a heel end elevational view of the FIG. 8 head; FIG. 13 is a rear elevational view of the FIG. 8 head; FIG. 14 is a top plan view of a third embodiment configured as a 2 wood;

(Description continued on next page.)

FIG. 15 is a front face elevation view of the FIG. 14 head;
FIG. 16 is a bottom plan view of the FIG. 14 head;
FIG. 17 is a toe end elevation view of the FIG. 14 head;
FIG. 18 is a heel end elevation view of the FIG. 14 head;
FIG. 19 is a rear elevation view of the FIG. 14 head;
FIG. 20 is a top plan view of a fourth embodiment configured as a 4 wood;
FIG. 21 is a front face elevation view of the FIG. 20 head;
FIG. 22 is a bottom plan view of the FIG. 20 head;
FIG. 23 is a top end elevation view of the FIG. 20 head;
FIG. 24 is a heel end elevation view of the FIG. 20 head;
FIG. 25 is a rear elevation view of the FIG. 20 head;

FIG. 26 is a top plan view of a fifth embodiment configured as a 5 wood;
FIG. 27 is a front face elevation view of the FIG. 26 head;
FIG. 28 is a bottom plan view of the FIG. 26 head;
FIG. 29 is a toe end elevation view of the FIG. 26 head;
FIG. 30 is a heel end elevation view of the FIG. 26 head;
FIG. 31 is a rear elevation view of the FIG. 26 head;
FIG. 32 is a section taken in elevation on lines 32—32 of FIG. 16;
FIG. 33 is a section taken in elevation on lines 33—33 of FIG. 16;
FIG. 34 is a section taken in elevation on lines 34—34 of FIG. 32; and,
FIG. 35 is a section taken in elevation on lines 35—35 of FIG. 32.
